UNITED STATES PATENT OFFICE.

WILLIAM H. SOUTHWICK, OF LEEDS, ENGLAND.

AIR OR WATER MOTOR.

1,076,713.

Specification of Letters Patent. Patented Oct. 28, 1913.

Application filed February 7, 1912. Serial No. 676,135.

To all whom it may concern:

Be it known that I, WILLIAM HERBERT SOUTHWICK, subject of the King of Great Britain, resident of the city of Leeds, county 5 of York, England, have invented certain new and useful Improvements in Air or Water Motors, of which the following is a full, clear, and exact description.

The invention relates to improvements in 10 air or water motors as described in the following specification and illustrated in the accompanying drawings that form part of the same.

The invention consists essentially in the 15 novel construction and arrangement of the parts of an air driven rotary member whereby the maximum area is presented to effect propulsion and the resistance to rotation is reduced to the minimum.

20 The objects of the invention are, to eliminate the heavy and cumbersome mechanisms at present in use in this class of motor and to devise a light and strong construction of motor which may be operated at high speed 25 and will develop a high percentage of power and by means of which the enormous amount of free energy in the air currents may be utilized to a much greater extent than hitherto.

30 In the drawings, Figure 1 is a perspective view of a motor constructed in accordance with this invention. Fig. 2 is a plan view of the motor with the top portions of the frame cut away.

35 Like numerals of reference indicate corresponding parts in each figure.

Referring to the drawings, 1 is a shaft which is stepped in a suitable form of bearing, preferably including balls or rollers, in 40 the standard 2 and projects upwardly therefrom.

3 is a circular block, rigidly secured to the shaft 1 immediately above the top of the supporting standard. A similar block is secured to the top end of the shaft.

4 are rectangular frames of light and rigid tubular construction open at one side and having the ends 5 rigidly secured in the blocks 3, and extending radially outward 50 therefrom. The horizontal portions 6 and 7 of said frames are preferably curved slightly in a lateral direction as clearly shown in the drawings.

8 are flat plates of thin metal secured to 55 the curved arms 6 and 7 of the tubular frames and have the straight radial edges 9.

The several finger shaped plates are rigidly secured together at the center and add very materially to the rigidity and strength of the frame though they do not add much 60 weight.

10 are a plurality of vertically arranged vanes of thin sheet material each having suitable rods or spindles secured at one of the vertical edges. The ends of the vane 65 spindles are journaled in suitable holes drilled in the inner sides of the curved arms 3 and 7 of the frames 4 and are so arranged that the outer edge of one vane slightly overlaps the spindle edge of the adjacent 70 vane. When the vanes are thus closed a very large and solid area is exposed to the wind pressure. The spindles are journaled free so that the vanes swing easily on their pivots and swing with the wind so that 75 only the back or spindle edge is presented to offer resistance to rotation. This is very clearly exemplified by the arrows shown in Fig. 2 of the drawings.

11 are small angular brackets secured to 80 the forward or front faces of the vanes 10 at the outer edges, said brackets having the swivel pins 12 rotatably secured therein.

13 are light steel rods extending through and secured in the pins 12 and forming connecting members uniting the outer free edges of the pivotal vanes so as to insure the vanes of each frame moving in unison and to obviate any tendency to flapping.

14 are spring fingers secured to the outer 90 vertical portions 15 of the frames 4 and arranged preferably in right angular relation to the vertical plane of each frame. These spring fingers form yielding stops to limit the outward swing of the vanes.

95 In the operation of this device, the moving air striking the vanes swings some of them closed and passes freely between others and as the vanes close a pocket is formed which receiving the pressure of a large 100 volume of air rotates the wheel with considerable force. The flat plates 8 serve effectively in preventing the spilling of the air at the top and bottom thus adding greatly to the efficiency.

105 From this description it will be readily understood that very great efficiency will be obtained and as the device is perfectly balanced it may rotate at very high speed without injury. The device may therefore 110 be readily adapted to the operation of power plants as batteries of these motors may be

utilized to operate electric generators and the power stored by the use of accumulators.

It will be also readily understood that this form of motor can be very easily adapted for use as a water motor.

What I claim as my invention is:—

In an air motor, a vertical shaft, a plurality of rectangular shaped frames having the top and bottom bars thereof curved horizontally in arc-shape, said frames extending radially from said shaft, horizontal plate members secured to the curved top and bottom bars in said frames and extending

across the chord of the arc thereof, and a plurality of pivotal vanes pivotally supported between the upper and lower curved bars and adapted to over-lap each other, and with the top and bottom plates forming air pockets.

Signed at Toronto, Canada, this 25th day of January, 1912.

WILLIAM H. SOUTHWICK.
